[57]**ABSTRACT**

A unit for converting a conventional chair into a rocking chair is disclosed. The conversion unit includes a pair of rocker assemblies, each having a right and left rocker member. The rocker members are positioned facing each other thereby forming a receiving volume capable of housing the legs of the conventional chair. The lower portion of the receiving volume is configured to have a longitudinal groove. The legs of the conventional chair are fitted with an elongated protruding member dimensioned to fit within the groove, and prevent the movement of the chair in relationship to the rocking assembly.

STANDARD CHAIR TO ROCKING CHAIR ADAPTER

TECHNICAL FIELD

The present invention relates to an assembly which can attach to the legs of a conventional chair, thereby providing the user with rocking capability.

BACKGROUND

Languishing in a rocking chair has been a long time source of relaxation and entertainment. However the majority of chairs on the market today can be classified as "standard" or chairs lacking the ability to rock back and forth. Therefore, much effort has been devoted to the development of an adapter which can convert a standard chair into a rocking chair. The desirable qualities of such a device fall into several categories including safety, durability, versatility, ease of conversion and convenience of use.

Many attempts have been made over the years to develop a conversion unit which can embody the above mentioned desirable qualities while still being affordable by the average consumer. Generally, these designs have been cumbersome to assemble, massive, and beyond the reasonable price range of any potential consumer.

For example, Clough (U.S. Pat. No. 4,126,353) is directed to a conversion unit for converting an ordinary standard chair into a rocking chair. However, a disadvantage of the device of the Clough patent is that the conversion unit disclosed has one piece rocker construction requiring the use of a telescoping brace between the two rockers in order to stabilize the assembly. This design is not advantageous to the user as it is difficult to assemble the telescoping braces required to stabilize the unit.

Clark (U.S. Pat. No. 2,612,489) discloses a rocker attachment for converting a stationary folding lawn chair, of tubular construction, into a rocking chair. This design, however, can only be utilized with chairs, preferably "lawn" chairs, of tubular construction. This unit is simply not an efficient means for conversion of a standard chair into a rocking chair.

Benzur (U.S. Pat. No. 5,013,086) discloses a device for converting a piece of furniture, such as a baby's crib, into a rocker. The conversion is accomplished by use of a one piece rocker, having a plurality of leg recesses in which the legs of a crib are placed. A disadvantage of the invention is that the rocker is not affixed to the leg of the crib thereby creating an unsafe and unstable condition.

Lerner (U.S. Pat. No. 5,246,268) directed to a device that attaches to the legs of a chair, by the use of straps which encircled the chair seat, thereby converting a standard chair into a rocking chair. This assembly, however, is difficult and cumbersome to assemble and operate. Another disadvantage of this invention is that the necessary straps are displeasing to the eye and can take away from the aesthetics of a chair.

The aforementioned references are directed to a device which can convert a Standard chair into a rocking chair. There continue to be improvements made in the design of such devices, with the objects of minimizing the difficulty of assembly and simplifying the design while still providing sufficient stability and safety for the user.

The devices for conversion of a Standard chair to a rocking chair now available on the market, such as those noted above, provide varying degrees of dual operation. This feature however, is gained at the expense of safety, stability, ease of installation and overall esthetic appeal. In accor-

dance with the present invention, these and other disadvantages of the prior art are minimized. The present invention provides a new and useful improvement on the traditional design of a Standard chair to rocking chair conversion device.

SUMMARY OF THE INVENTION

The invention, as claimed, is intended to provide an improved standard chair to rocking chair adapter. The present invention affords the user the ability to convert a standard chair into a rocking chair with a minimum of inconvenience and expense while still providing a safe and stable chair.

The preferred embodiment of the present invention comprises a Pair of arcuate rocking elements. Each of said rocking elements is configured in two pieces. When the two pieces are secured to one another a receiving area is formed. This receiving area runs along the length of the rocking assembly, and provides a volume which can house the legs of the conventional chair. Along the lower portion of the receiving area is a groove.

Each of the legs of the conventional chair is fitted with an elongated protruding member. The portion of said member that extends beyond the width of the chair is housed within the groove running along the lower portion of the receiving area. After the protruding member is secured within the groove the chair cannot move in relation to the rocking assembly.

BRIEF DESCRIPTION OF THE DRAWINGS

One way of carrying out the invention is described in detail below with reference to drawings which illustrate only one specific embodiment of the invention and in which:

FIG. 1 is a perspective view of a standard chair to rocking chair conversion unit constructed in accordance with the preferred embodiment of the present invention shown attached to said standard chair;

FIG. 2 is a side elevation of a rocker member taken along lines 2—2 of FIG. 1;

FIG. 3 is a cross sectional view of a rocker member taken along lines 3—3 of FIG. 2;

FIG. 4 is a top view of a conversion unit constructed in accordance with the preferred embodiment of the present invention;

FIG. 5 is a perspective view of the conversion unit;

FIG. 6 is a cross sectional view of the conversion unit taken along section lines 6—6 of FIG. 5;

FIG. 7 is a perspective view of an alternative embodiment of the conversion unit;

FIG. 8 is a cross sectional view of alternative embodiment of the conversion unit taken along section lines 8—8 of FIG. 7;

FIG. 9 is a partial elevation of the rocker element as constructed in accordance with the alternative embodiment of FIG. 7;

FIG. 10 is a perspective view of an alternative embodiment of the conversion unit; and

FIG. 11 is a cross sectional view of an alternative embodiment of the conversion unit taken along section lines 1—11 of FIG. 10.

DETAILED DESCRIPTION OF THE PREFERRED EMBODIMENTS

Referring to FIG. 1, the inventive standard chair to rocking chair conversion unit is illustrated. Conversion unit

10 comprises a pair of rockers **12** which attach to the legs **14** of a Standard chair **16**. Rockers **12** have a right rocker member **18** and a left rocker member **20**. Rocker **12** can be constructed out of any material of sufficient strength to support chair **16**, while still being lightweight enough to allow the user to manipulate the rocker members during assembly. Rocker **12** is preferably made of high strength plastic, however wood or metal can also be used.

Right rocker member **18** and left rocker member **20** are mirror images of each other, which are held together by screws **22**. As seen in FIG. 2, right rocker member **18** has a curved surface **24**, an upper surface **26**, and an inner surface **28**. Right rocker member **18** also has a receiving area **30** which is defined by a pair of longitudinal sides **32**, and a lower surface **34**. Receiving area **30** is also configured with a groove **36**, and a well **38**.

Right rocker member **18** also has a pair of holes **40** which can receive screws **22**. FIG. 3 clearly shows groove **36** and well **38** of receiving area **30**. Also shown is the side wall **42** of receiving area **30**. Groove **36** is recessed into side wall **42**. Well **38** is similarly recessed into lower surface **34** of receiving area **30**. The actual dimensions of receiving area **30**, and its components can vary to accommodate a wide variety of chair leg sizes and shapes.

FIG. 4 shows right rocker member **18** and left rocker member **20** of conversion unit **10** in their assembled positions. The two halves of conversion unit **10** are held together by screws **22** which pass through holes **40**. Screws **22** can consist of a machine screw and wing-nut assembly utilizing a washer on the outer walls **42** of rocker members **18** and **20**. Alternatively screws **22** may be held in place by a locking nut assembly or any other methods used in the industry.

FIG. 5 shows the conversion unit **10** after assembly to a Standard chair leg **44**. Chair leg **44** is shown having a round configuration, however the conversion unit can be adapted to fit a square leg or any other shape which may be used. The leg **44** is fitted with a bar **46**. Bar **46** is attached to leg **44** by the use of a fastener **48**.

As shown in FIG. 6 the fastener **48** is in the form of a screw which is threaded into the leg **44**. The illustrated use of a screw shall not preclude the use of a pinning, press, or tack welding, or any other manner of fastening. Bar **46** is wider than leg **44** and fits into groove **36** of receiving area **30**. Similarly the head of fastener **48** fits into well **38** so that rocker members **18** and **20** join together without any interference.

When it is desired to fit a standard chair with the inventive conversion unit **10**, the chair legs must be fitted with a bar **46**. It is preferred that the chair have four legs which have solid portions at their feet. However this is only necessary if the user wishes to fasten bar **46** to leg **44** using a self tapping screw. The user can fasten bar **46** to leg **44** using the alternative methods mentioned above or any other method known in the industry. Once the chair is fitted with bar **46**, rocker members **20** and **18** are then mated together such that bar **46** is placed within groove **36**. The rocker members are then held together by use of screws **22** which pass through hole **40**. This process forms rocker **12**. This process is then repeated securing another rocker assembly **12** to the other two chair legs.

In order to accommodate a wide range of chair leg spans, groove **36** runs substantially the entire length of receiving area **30**. The extended length of groove **36** allows for the differences found in the typical span of chair legs.

When in use the conversion unit **10** provides a stable base which enables the user to rock a standard chair back and

forth. The curved portion **24** of rocker members **18** and **20** provides a smooth transition when the user shifts their weight from front to rear, on the chair. When the user shifts their weight into the back rest of the chair the tendency will be for the front legs of the chair to rise up out of receiving area **30**. However the novel design of rocker assembly **12** prevents this from happening. Bar **46** which is situated in groove **36**, and fastened to leg **44**, will prevent the chair from moving in relation to the rockers.

10 In FIG. 7, an alternative embodiment of the present invention is illustrated. Generally similar components or parts performing analogous, corresponding or identical functions to those of the FIG. 1 embodiment are numbered herein with numerals which differ from the FIG. 1 embodiment by multiples of one hundred.

Referring now to FIG. 7 rocker assembly **112** has a right rocker member **118** and a left rocker member **113** which are held together by screws **122**. Rocker assembly **112** holds chair legs **144** in place. The curved portion **124** of rocker members **118** and **120** allows the user to rock the chair back and forth by shifting their weight.

20 FIG. 8 depicts the alternative method of securing chair leg **144** within rocker assembly **112**. As in the previous embodiment rocker members **118** and **140** are mirror images of one another. Each has a receiving area **130** a side wall **132**, and a lower portion **134** which has a well **138**.

25 Secured to the lower portion of leg **144** is a bracket **152** which is held in place by a fastener **150**. Fastener **150** is preferably a self tapping screw, however any method known can be used to fasten bracket **152** to chair leg **144**, such as aforementioned. Bracket **152** is held within rocker assembly **112** by use of an expansion stopper **154**. Expansion stopper **154** is of the type which can be placed within receiving area **130** and then its size is expanded to wedge itself within rocker members **118** and **120**. The use of expansion stopper **154** will prevent chair leg **144** from moving in relation to the rocker assembly **112**.

30 As shown in FIG. 9, bracket **152** has a greater length than the lower portion of leg **144**. This allows expansion stopper **154** to rest on top of bracket **152**, thereby preventing movement of leg **144** in relation to rocker assembly **112**.

35 In FIG. 10, another alternative embodiment of the present invention is illustrated. Generally similar components or parts performing analogous, corresponding or identical functions to those of the FIG. 1 embodiment are numbered herein with numerals which differ from the FIG. 1 embodiment by multiples of one hundred.

40 FIG. 10 shows yet another alternative embodiment of the present invention. Rocker assembly **212** has a right rocker member **218** and a left rocker member **220** which are held together by fasteners **222**. Secured between the right and left rocker members is leg to **44**.

45 As can be clearly seen in FIG. 11, leg **244** is held in place by grasping friction pads **258**. Friction pads **258** have fins **260** which are angled downward to prevent leg **244** from sliding out of receiving area **230** when the chair is rocked. Friction pads **258** are constructed from any material such as rubber, which will prevent the slippage of leg **244**, while at the same time preventing damage from occurring to leg **244**.

50 While an illustrative embodiment of the invention has been described above, it is, of course, understood that various modifications will be apparent to those of ordinary skill in the art. Such modifications are within the spirit and scope of the invention, which is limited and defined only by the appended claims.

I claim:

1. A pair of rocker assemblies for attachment to a standard chair having four legs, to convert said standard chair into a rocking chair, each of said rocker assemblies, comprising:
- (a) a right rocker element, said right rocker element having an inner left side, an outer right side, a top side, and a curved bottom surface, said right rocker element comprising:
    - (i) a right sidewall defined in said inner left side of said right rocker element;
    - (ii) a right chair leg support surface defined in said inner left inside of said right rocker element and extending substantially transverse to said right sidewall in said right rocker element, and from said right sidewall to the inner most portions of said left side of said right rocker element;
    - (iii) a right rocker element support surface comprising said curved bottom surface of said right rocker element and being substantially transverse to said chair leg support surface extending downwardly therefrom;
  - (b) a left rocker element, said left rocker element having an inner right side, an outer left side, a top side, and a curved bottom surface, said left rocker element being positioned with respect to said right rocker element with said inner right side of said left rocker element in facing relationship to said inner left side of said right rocker element, said left rocker element comprising:
    - (i) a left sidewall defined in said inner right side of said left rocker element;
    - (ii) a left chair leg support surface defined in said inner right inside of said left rocker element and extending substantially transverse to said left sidewall in said left rocker element, and from said left sidewall to the inner most portions of said right side of said left rocker element;
    - (iii) a left rocker element support surface comprising said curved bottom surface of said left rocker element and being substantially transverse to said chair leg support surface extending downwardly therefrom, said right sidewall, said left sidewall, said right chair leg support surface and said left chair leg support surface together defining a receiving volume having a width, a length, and a depth, said width being defined between said right and left sidewalls of said right and left rocker elements, and said length being sufficient to allow the housing of two of the chair legs of said chair in said receiving volume;
  - (c) a right groove defined longitudinally within said right sidewall;
  - (d) a left groove defined longitudinally within said left sidewall; and
  - (e) a plurality of protruding engagement members for attachment to the bottom of each of said chair legs, each of said engagement members extending beyond said receiving volume, and said engagement members being engaged by said right and left grooves defined longitudinally within said right and left sidewalls, said grooves and said engagement members being configured, positioned and dimensioned to restrict movement of said engagement members and the bottoms of said chair legs in relation to said rocker assembly.
2. A kit for converting a standard chair having four legs into a rocking chair, comprising: two substantially similar rocker assemblies each being formed by two substantially similar rocker elements, each of said rocker assemblies comprising:

- a) a curved bottom surface;
- b) a chair leg support surface;
- c) a receiving area having a length, width, and depth and extending into said rocker assembly, the width of said receiving area being substantially defined by a left receiving area sidewall and a right receiving area sidewall and the depth of said receiving area being substantially defined by the distance from the uppermost parts of said left and right receiving area sidewalls to said chair leg support surface, said receiving area comprising a volume within said rocker assembly sufficiently large enough to allow insertion of two of four of said chair legs; and
- d) recessed grooves defined longitudinally within said right and left receiving area sidewalls having a volume sufficient to allow engagement of a plurality of protruding engagement members releasably attachable to the bottom of each of said chair legs, said engagement members protruding substantially perpendicularly away from the planar surface of said chair legs and beyond said right and left receiving area sidewalls into said recessed grooves.
- 3. A kit according to claim 2, whereby said rocker elements are constructed from wood.
- 4. A kit according to claim 2, whereby said rocker elements are constructed from plastic.
- 5. A kit according to claim 2, wherein said rocker elements are secured together to form a rocker assembly by engaging at least one fastener substantially transversely through each of said rocker elements.
- 6. A kit for converting a standard chair having four legs into a rocking chair, comprising: two substantially similar rocker assemblies having two substantially similar rocker elements attached together, each of said rocker assemblies comprising:
  - a) a curved bottom surface;
  - b) a chair leg support surface;
  - c) a receiving area having a length, width, and depth and extending into said rocker assembly, the width of said receiving area being substantially defined by a left receiving area sidewall and a right receiving area sidewall and the depth of said receiving area being substantially defined by the distance from the uppermost parts of said left and right receiving area sidewalls to said chair leg support surface, said receiving area comprising a volume within said rocker assembly sufficiently large enough to allow insertion of two of four of said chair legs; and
  - d) a recessed groove defined longitudinally within said right and left receiving area sidewalls having a volume sufficient to allow engagement of a plurality of protruding engagement members releasably attachable to the bottom of each of said chair legs, said engagement members protruding substantially perpendicularly away from the planar surface of said chair legs and beyond said right and left receiving area sidewalls into said recessed grooves;
  - e) a fastener for releasably attaching said protruding engagement member to said chair leg, said fastener having a first end and a second end, said first end capable of being inserted through said protruding engagement member and into the bottom of said chair leg and said second end being wider than said first end; and
  - f) a recessed well defined longitudinally within said bottom receiving area surface, configured, dimensioned

and positioned to have a volume sufficient to accommodate said second end of said fastener.

7. A kit according to claim 6, whereby said rocker elements are constructed from wood.

8. A kit according to claim 6, whereby said rocker elements are constructed from plastic. 5

9. A kit according to claim 6, wherein said rocker elements are secured together to form a rocker assembly by engaging at least one connecting element substantially transversely through each of said rocker elements.
